HAIR CURLER AND METHOD OF ASSEMBLY

William Huppert, New York, N. Y., assignor to
Delamere Company, Inc., a corporation of
Delaware

Application July 15, 1939, Serial No. 284,616

12 Claims. (Cl. 132—41)

This invention relates to the manufacture of a hair curler of the type having a tubular member or form around which the hair is wound, and a wire loop clamping member pivotally connected to the curler to be swung over and around the wound hair. The curler is provided with a semi-tubular member which is pivotally secured by means of the loop to the tubular member for catching the ends of the hair between the two members prior to winding. In some instances, both the tubular and the semi-tubular member are provided with handles and with a spring urging the two members closed.

The loop is generally made of a single piece of resilient wire formed with inturned ends that are passed through aligned openings in the tubular and semi-tubular members.

The present practice is to assemble the parts and then to attach the loop thereto by first manually inserting one end of the loop into openings at one side of the curler and then inserting the other end into openings in the opposite side.

This is a rather slow and tedious operation which materially increases the cost of production and has the further disadvantage that a loop having disconnected inturned ends is apt to become detached from the curler in use.

To prevent the likelihood of accidental detachment, it has heretofore been proposed to bend or curve the ends of the loop either before or after they have been inserted into the curler. It has also been proposed to solder the ends of the loop after it has been assembled with the curler, or to couple the ends with a surrounding sleeve. However, in all of these practices it has been necessary to insert each of the two ends of the loop separately in the openings or holes in the curler, and to perform the additional operations of bending or of connecting the ends with solder or with a sleeve after insertion, all of which operations increase the cost and decrease the speed of production.

The tubular and the semi-tubular members of such curlers are generally made from sheets of metal, such as aluminum or the like, cut, shaped and bent to form. More recently it has been proposed to form these parts of molded plastic substance, such as cellulose acetate composition, plastic synthetic resins, and the like.

All of the parts of the curler are manufactured mechanically at high speed and low cost. One of the principal items of labor cost, and one that is out of all proportion to the labor cost of manufacture of the parts, has heretofore been the manual labor involved in attaching the ends

of the loop to the curler. Not only has this increased the cost of manufacture excessively but it has also materially reduced the rate of production of the finished articles.

The principal objects of this invention are to reduce the cost of manufacture, to provide curlers of this type with wire loop members that cannot become accidentally detached, and to provide a construction whereby the rate of production of the finished articles is accelerated. 5

A further object of the invention is to provide a curler with a wire loop clamp the ends of which are connected together, to form a closed loop, prior to assembly of the loop with the other parts.

Another object is to provide a curler of such construction that it may be manufactured without the necessity of the laborious operation of inserting each end of the loop separately into aligned openings in the tubular and semi-tubular members of the curler. 10

Other objects and advantages of the invention will appear to those skilled in the art from the following description thereof, reference being had to the accompanying drawings, in which:

Fig. 1 is a top plan view of a metal curler 25 embodying the invention;

Fig. 2 is a side elevation thereof, showing the assembly tools or dies in dotted lines;

Fig. 3 is a rear end view of the curler of 30 Figure 1;

Fig. 4 is a rear end view similar to Fig. 3 showing the parts prior to complete assembly;

Figs. 5 and 6 are fragmentary perspective views of the tubular and the semi-tubular members, respectively, prior to assembly; 35

Fig. 7 is a side elevation of a modified form of curler with the ends broken off;

Fig. 8 is a cross-sectional view thereof, prior to complete assembly, on the line 8—8 of Fig. 7;

Figs. 9—12 are detail views of the assembly tools 40 or dies;

Fig. 13 is a side elevation of a curler of molded plastic material embodying the invention;

Fig. 14 is a sectional view thereof on the line 45 14—14 of Fig. 13;

Fig. 15 is a fragmentary side view of the tubular member prior to assembly;

Fig. 16 is a similar view of the semi-tubular member;

Fig. 17 is a fragmentary bottom plan view of 50 the semi-tubular member prior to assembly showing an assembly tool or die in relation thereto;

Fig. 18 is a similar view showing the member as it appears after assembly; 55

Fig. 19 is a view similar to Fig. 17 showing a modification of the semi-tubular member;

Fig. 20 is a view of this modification similar to Fig. 18; and

5 Fig. 21 is a plan view of the wire loop clamping member.

The device, in these various modifications, comprises the usual tubular member or form 10 and semi-tubular member or finger 11 common

10 in the manufacture of curlers of this type. These parts may be made of metal or molded plastic material. If desired, the semi-tubular member 11 may be omitted. The device also preferably comprises a wire loop clamping member 12 which 15 differs, however, from the usual wire clamp in that its ends are preferably welded or connected together at 13, as best seen in Fig. 21, prior to the assembly of the loop with the other parts of the curler.

20 A springless type of curler, having metal tubular and semi-tubular members, is shown in Figs. 1-6, inclusive. Each of these members has a pair of opposed openings or perforations 14 and 15, respectively, near one end, and slits 16 and 17, respectively, leading from the exterior to the corresponding openings. The metal at the slits is bent out of its normal plane to provide an open passage of greater width than the diameter of the wire of the loop 12 through which, when the 25 two members are assembled, the closed loop 12 may be freely passed into the aligned openings. The bent parts are subsequently rebent into their normal plane to close the passage and to confine the loop in the aligned openings 14, 15.

30 It will be observed that the loop is fulcrumed in the openings to swing over and around the tubular and semi-tubular members and that those members are pivotally connected together by that portion of the loop that passes transversely 35 through the openings and serves as a pin about which the members pivot. The outer end of the loop may be provided with the usual roller 18 fastening the loop in closed position, although the roller may be omitted and the loop may be 40 secured in closed position in any other known manner. In some forms of the invention the loop may be omitted and a pivot pin may be used 45 for pivotally securing the two members together.

50 In Figs. 7 and 8 is shown the form of curler in which each of the metal members 10 and 11 has a rearwardly extending handle portion 19 between which a spring 20 is disposed for urging the members closed. In this instance, as in the previous described form, each of the members 55 has aligned openings 14, 15 for reception of the closed loop 12, and slits 16 and 17, respectively, leading from the exterior to the corresponding openings. The slits are opened by bending portions of the metal at the slits, as seen in Fig. 8, 60 to provide a passage through which the closed loop member may be inserted into the aligned openings. The bent portions are then rebent to their normal position to close the passages against withdrawal of the loop.

65 Any suitable tools or dies may be employed for closing the passages. A form of such tools is shown in Figs. 9-12, wherein 21 is an arbor having a rounded conical head 22 formed with a slot or recess 23. The arbor is inserted and forced 70 into the opening at the rear end of the curler to bend or swage the inwardly bent portions 24 back to normal position. The slot or recess 23 in the arbor provides clearance for the closed loop 12, which as above noted, is placed in the assembly 75 prior to this bending operation. 25 is an outer

die having a pair of arms 26 that pass over the outer surface of the assembly to rebend the outwardly bent portions 27 into their normal position.

80 Various adaptations of the structure for use in the manufacture of curlers having tubular and semi-tubular members made of molded plastic material are shown in Figs. 13-20, inclusive. As there shown, the tubular member 10 has a slot 28 leading to the openings 29, and has formed on its external surface recesses 30 in which the ear portions of the semi-tubular member 11 fit, as seen in Fig. 14. After the closed loop 12 has been inserted through the slot into the openings, the corners or edge portions 31 are upset or 15 pressed down, as indicated by the dotted lines in Fig. 15, to close the slot and hold the loop in assembled position.

20 The plastic semi-tubular member, as seen in Fig. 16, has slots 32 that are adapted to pass over the loop 12 when the latter is assembled to the tubular member, and lead to openings 33. After assembly of the parts, as seen in Figs. 13 and 14, portions of the material adjacent the slots 32 25 are pressed out to provide protrusions 34 that close the slots immediately below the openings. In connection with Fig. 17, there is shown a tool or die 35 for forming the protrusions 34 as shown in Fig. 18. In Fig. 16 the protrusions are indicated by dotted lines.

25 A modification of the semi-tubular member is shown in Figs. 19 and 20 wherein that member is initially molded with lateral projections 36 that are pressed down to close the slots 32. A tool 37 30 for this purpose is indicated by the dot-and-dash lines in Fig. 20.

35 It will be seen from the foregoing description that the construction of the curler is such that a preformed, completely closed loop may be readily and easily applied to the curler, and that when the parts are assembled, they will be retained in proper relation to each other.

40 While I have described my invention with reference to specific forms thereof, it will be understood that various changes may be made therein 45 without departing from the spirit of the invention.

45 What I claim is:

1. A hair curler comprising a form of substantially circular cross-section around which the hair may be wound, an opening extending transversely through the form adjacent one end, passages leading to said opening from the exterior of the form, a closed wire loop clamping member fulcrumed in the opening and adapted to be 55 swung into position over the opposite end and around the form to embrace the hair wound thereon, said form having integral portions that close the passages leading into the opening to prevent removal of the clamping member. 60

2. A hair curler comprising a metal tube of substantially circular cross-section around which the hair may be wound, opposed perforations in the sides of the tube adjacent one end, slits leading to said perforations from the exterior of the tube, a closed wire loop clamping member fulcrumed in said perforations and adapted to be 65 swung into position over the opposite end and around the form to embrace the hair wound thereon, said tube having portions of the metal at the slits initially bent out of their normal plane to permit of insertion of the closed loop through the slits into the perforations, and subsequently 70 bent back into their normal plane to close the 75

slits and prevent removal of the clamping member.

3. A hair curler comprising a tube of molded plastic material of substantially circular cross-section, an opening extending transversely through the tube adjacent one end, a closed wire loop clamping member fulcrumed in the opening, slots leading to said opening from the exterior of the tube, said tube having deformed integral portions that protrude over and close the slots to prevent removal of the clamping member.

4. A hair curler comprising a tubular member of substantially circular cross-section, a finger member of arcuate shape cross-section substantially corresponding to the curvature of the tubular member mounted on and adapted to lie over said member, an opening extending transversely through both members near one end, a wire loop clamping member fulcrumed in the opening, passages leading from the exterior of each member to the opening, said passages being initially open to permit of insertion of the clamping member and subsequently closed to prevent removal thereof.

5. A hair curler comprising a tubular member, a semitubular member mounted to lie over the tubular member, aligned openings in both members near one end, slits in both members extending from the exterior to the openings and having portions of the members adjacent the slits initially bent out of their normal plane, a closed wire loop member fulcrumed in the openings and held therein against removal by portions of the members adjacent the slits rebent to their normal plane.

6. A hair curler comprising a tubular member, a semi-tubular member lying over the tubular member, aligned openings through both members near one end, a closed wire loop member fulcrumed in the openings, slots in both members extending from the exterior to the openings, and deformed portions of both members closing the slots to secure the wire loop permanently in the opening.

7. A hair curler comprising a tubular member, a semi-tubular member lying over the tubular member, both of said members having handle portions, aligned transverse openings through overlapping portions of said members, slits leading from the exterior to the openings and portions of the members adjacent the slits bent initially out of their normal plane, a closed wire loop fulcrumed in said openings and pivotally connecting the tubular and semi-tubular members, said loop being confined in the openings by portions of the members adjacent the slits rebent to their normal plane.

8. The method of assembling a wire loop to a hair curler having a tubular and a semi-tubular

member, which comprises providing aligned openings in both members for reception of the loop, cutting slits in said members from the exterior to the openings, bending the material of each member adjacent the slits out of its normal plane to provide a passage through which the loop may be inserted into the openings, inserting the loop through said passages into the openings, and subsequently rebending the material back into its normal plane to close the passages leading to the openings.

9. The method of assembling a wire loop to a hair curler having a tubular and a semi-tubular member, which comprises providing openings in said members for reception of the loop, forming passages in both members leading from the exterior to said openings of greater width than the diameter of the wire of the loop, inserting the loop through said passages into the openings, and deforming portions of the material adjacent the passages to close said passages against withdrawal of the loop from the openings.

10. The method of assembling a pivot to a hair curler having two cooperating members, which comprises providing aligned openings in both members for reception of the pivot, cutting slits in said members from the exterior to the openings, bending the material of each member adjacent the slits out of its normal plane to provide a passage through which the pivot may be inserted into the openings, inserting the pivot through said passages into the openings, and subsequently rebending the material back into its normal plane to close the passages leading to the openings.

11. The method of assembling a pivot to a hair curler having two cooperating members, which comprises providing openings in both members for reception of the pivot, forming passages in both members leading from the exterior to said openings of greater width than the diameter of the pivot, inserting the pivot through said passages into the openings, and deforming portions of the material adjacent the passages to close said passages against withdrawal of the pivot from the openings.

12. A hair curler comprising a form around which the hair may be wound, a finger member mounted on and lying over said form, an opening extending transversely of both the form and the finger adjacent one end thereof, a pivot fulcrumed in the opening, passages leading to said opening from the exterior of both the form and the finger, said passages being initially open to permit of insertion of the pivot into the opening and subsequently closed to prevent removal thereof by integral portions of the material of the form and the finger adjacent said passages.
